Gustavo Marin(57) **CLAIM**

The ornamental design for a mobile device enclosure, as shown and described.

DESCRIPTION

FIG. 1 is a right-front isometric view of a mobile device enclosure;

FIG. 2 is a left-front isometric view thereof;

FIG. 3 is a front elevational view thereof;

FIG. 4 is a rear elevational view thereof;

FIG. 5 is a top plan view thereof;

FIG. 6 is a bottom view thereof;

FIG. 7 is a left elevational view thereof;

FIG. 8 is a right elevational view thereof;

FIG. 9 is a left-rear isometric view thereof; and,

FIG. 10 is a right-rear isometric view thereof.

1 Claim, 8 Drawing Sheets(56)
